UNITED STATES PATENT OFFICE.

HARRY J. ARKUS, OF PHILADELPHIA, PENNSYLVANIA.

TOOTHBRAHSH.

Application filed May 8, 1923. Serial No. 637,440.

To all whom it may concern:

Be it known that I, HARRY J. ARKUS, a subject of Ferdinand I, King of Roumania (the applicant having made application for citizenship of the United States on July 21, 1921), residing at Philadelphia, in the county of Philadelphia and State of Pennsylvania, have invented certain new and useful Improvements in Toothbrushes, of which the following is a specification.

The object of this invention is to provide improvements in brushes for cleansing the teeth.

Another object is to provide a brush which is adapted to cleanse both the outside and inner side of a row of teeth simultaneously, that is, with the same manual effort and motion of the hand, instead of first brushing the outer and then the inner surfaces of the teeth.

A further object is to provide such an article, comprising a brush member pivotally mounted upon the end portion of a handle, whereby the angle formed by the bristles of the brush with the handle is altered at will, or automatically, as the handle when held is substantially one position is oscillated about the curvature of a set of teeth.

Still another object is to provide in such an article a second brush member pivotally mounted both with respect to the said handle and the first brush member, so that upon oscillating the handle in the usual manner the shape of the space between the bristles of the brushes changes, as the relation of the combined brushes to the handle changes.

And a still further object is to provide in such an article a pair of oppositely positioned brushes, the brush-backs, or the planes of the respective bristle tips of the two brushes, converging in one direction to conform substantially with the tapering character of the teeth, while the pivotal relation of one brush with respect to the other changes so that at one end the opposed bristles are in proximity for uniform contact with the frontal teeth, and at the other end the opposed bristles are widely spaced apart to admit therebetween the thicker teeth in the sides of the jaw.

With these and other objects in view, the present invention comprises further novel details of construction and operation hereinafter fully brought out in the following description, when read in conjunction with the accompanying drawings, in which Fig. 1

is a top plan view of one embodiment of the invention, showing the brushes in a central position; Fig. 2 is a central longitudinal section of the brush as shown in Fig. 1; Fig. 3 is a plan view of the improved article, with the brushes oscillated in one direction with respect to the handle, and one of the brushes oscillated with respect to the other; and Fig. 4 is a bottom plan view of the brush or article in the position shown in Fig. 1.

Referring to the drawings, any suitably shaped handle 1 is provided, the same being bent and provided at one end 2 with a flattened head 3, having a centrally, transversely extending, bore 4, receiving one end of a rivet 5 or other means for pivotally mounting upon said head a suitably shaped base member 6. Said base member is angularly directed at one end portion and transversely extended in opposite directions in such manner as to form a curved brush-back 7, provided with the usual type of bristles 8, which, if preferred, may have their end portions 9 tapered for entering the interstices between the teeth of the user in the most efficient manner.

The opposite end portion of the said base member is extended oppositely to form a bearing portion 10, having an outwardly positioned face 11, and provided with a transversely positioned aperture 12, through which extends a rivet or other pivotal member 13.

Supported upon the bearing portion 10 is the body portion 14, provided with a transversely positioned aperture 15, through which extends the pivot member 13, said body portion extending angularly outwardly, and preferably at substantially right angles to the bearing portion 10 to provide a brush-back 16, comprising oppositely extending portions suitably curved and provided with bristles 17, which, if desired, may be cut at the free ends 18 as are the bristles 8 at their end portions 9.

In this construction, it will be noted that the base portion 6 is mounted to rotate or at least oscillate about the rivet 5, which extends through an aperture 19 in said base portion. Thus, when the brush 7 is in the position shown in Fig. 3, the position of the curved plane of the free end portions of the bristles is such as to correspond with the curvature of the teeth of the right lower jaw, or the upper left jaw, when the handle

1 is held substantially directly in front of the face of the user.

When the brush 7 is in this position, it will be noted that the brush 16 has oscillated 5 about the pivot 13, in such manner that the distance between the opposed bristles of the two brushes at one end is less than the distance between the opposite end portions of the said brushes, for the reason that the 10 teeth between the nearer bristles, being the front teeth of either the upper or lower jaw, are thinner or of less transverse extent from inside to outside than are the teeth of the side and rear portions of the jaws.

15 Obviously then, as the brush-handle is moved outwardly and thence laterally, so that the pivot 5 moves in an arc conforming with that of one's jaw, the bristles of the brush 7 will follow the outer surface of the 20 teeth, while the bristles of the brush 16 follow the inner surfaces of the teeth until the base member 6 has moved angularly into a similar position upon the opposite side of, and in angular relation with, the handle, 25 and the brush 16 has oscillated upon said base member with respect to the brush 7, so that the brush ends, more distinctively 30 separated in Fig. 3, have approached each other into close relationship, while the brush ends adjacent to each other in said Fig. 3 have become separated for the purpose of 35 permitting the entrance of the teeth of gradually changing thickness upon the opposite sides of the jaw, that is, upon the left side of the lower jaw, or the right side of the upper jaw.

It will at once be observed that this invention is not limited to the exact angular relationship shown as existing between the 40 brushes as illustrated, nor the proportionate distance separating the brushes of a given article, for the reason that the thickness of teeth of minors is much less than of the teeth of adults, while it is also true that the 45 thickness of teeth and the radii of the arcs of the teeth in adults differ materially.

While a single embodiment of the invention has been described in detail, it is to be understood that the scope of the invention, broadly speaking, is to be determined solely by the scope of the claims here-to appended.

Having thus described my invention, what I claim and desire to protect by 55 Letters Patent of the United States is:—

1. An article, comprising a member adapted to be used as a handle, a base member pivotally carried by said first member, a brush fixedly mounted upon and operative 60 to move with said second member in respect to said first member, and a second brush pivotally carried by said second member and movable both with respect to said first and second members.

2. An article, comprising a handle, a base 65 member pivotally carried by one end portion of said handle and having a laterally disposed integral extension, a brush integrally secured to said extension, said base member also having an integral angularly 70 disposed extension, and a second brush pivotally carried by said angularly disposed extension and adapted to oscillate both with respect to said handle and with said first 75 brush, the ends of the bristles of the respective brushes lying in substantially concentrically curved planes angularly disposed with respect to each other to provide a tapering space between them to accommodate teeth of the average shape.

3. An article, comprising a handle, a base member pivotally carried by one end portion of said handle and having an extension, a brush integrally secured to said extension and adapted to oscillate with respect to said handle, and a second brush pivotally carried by said base member and angularly disposed with respect to said first brush, said second brush being adapted to oscillate both with respect to said handle and said first 90 brush.

4. An article, comprising a handle, a base member pivotally carried by one end portion of said handle and having an extension, a brush integrally secured to said extension and adapted to oscillate with respect to said handle, said base member having a portion angularly disposed with respect to said brush, and a second brush pivotally carried by said angularly disposed portion so that the axes of oscillation of said base member and the second brush are angularly related, said second brush being adapted to oscillate both with respect to said handle and said first brush, and in a moving plane angularly disposed with respect to the fixed plane of movement of said first brush.

5. An article, comprising a handle, a base member pivotally carried by one end portion of said handle and having a laterally disposed integral extension, a brush integrally secured to said extension, said base member also having an integral angularly disposed extension, and a second brush pivotally carried by said angularly disposed extension and adapted to oscillate both with respect to said handle and with said first brush, the ends of the bristles of the respective brushes lying in substantially similarly curved planes, and by virtue of the angular relationship of the said extensions said planes being angularly disposed with respect to each other to provide a tapering space between the bristles to accommodate the average shaped teeth.

In testimony whereof I have affixed my signature.

HARRY J. ARKUS.
